UNITED STATES PATENT OFFICE

2,446,301

SELF-CENTERING FUNNEL

Seddon C. Nelson, Front Royal, Va., assignor to
American Viscose Corporation, Wilmington,
Del., a corporation of Delaware

Application September 7, 1945, Serial No. 615,017

5 Claims. (Cl. 57—76)

1

The present invention relates to a thread guide adapted to control the delivery of filaments, yarns and the like into centrifugal buckets, such as are used for collecting freshly spun filamentary material during their production on artificial filament spinning machines.

The principal object of the present invention is to provide a self-centering funnel so that if the funnel should happen to be mounted in an off-center position, it will automatically center itself simply by virtue of the pull of the yarn at the discharge end of the funnel. Other objects and advantages of the present invention will be apparent from the drawing and description thereof hereinafter.

The drawing is illustrative of preferred embodiments and—

Figure 1 thereof is an elevation in cross-section showing the mounting of the guide and its relationship to a spinning bucket,

Figure 2 is an elevation of the spherical bearing surface provided on the guide, and

Figure 3 is an elevation showing a modification.

In general, the present invention provides a spherical bearing for the funnel which allows a certain amount of oscillation of the funnel within the bearing. The center of gravity of the guide and the portion of the bearing which moves with it is substantially at the center of the spherical bearing surface and damping means is provided to retard the movements of the guide.

As shown in Figures 1 and 2, a guide 2 having the general shape of a funnel is supported on a bracket 3 adapted to be carried by the traverse rail of the spinning machine and the funnel discharges the thread 4 from its lower end into the rapidly rotating spinning bucket 5 which may be driven in conventional manner and has a conventional cover 6 secured in place by any conventional means such as a rubber ring 7. The bracket 3 carries a socket member 8 having a spherical bearing surface 9 and a bore 10 substantially greater in diameter than that of the guide. The guide 2 is secured within the sleeve 11 of a floating bearing 12. The lower end of sleeve 11 is somewhat enlarged to provide a spherical bearing surface 13 adapted to cooperate with the spherical bearing surface 9 within the socket member 8. Damping means is provided between socket member 8 and the floating bearing 12. As shown, this means may take the form of an annular well 14 within the socket member 8 and an annular skirt 15 depending from the bearing member 12 and extending into the well 14. In

2

operating position as shown, the skirt 15 is spaced at all portions from the adjacent walls defining the interior of the well 14 and the space between the skirt 15 and the walls of the well 14 is at least partially filled with a viscous liquid 16. The bearing member 12 may be provided with a rim 17 which overhangs but is spaced from the upper edge of the outer wall of well 14. The sleeve 11 is also spaced from the inner wall of the well 14, so that the floating bearing 12 is at all points free to swing about the spherical joint defined by the spherical surfaces 9 and 13.

Figure 3 shows a modification which is substantially identical with that shown in Figure 1, except that two annular sealing sleeves 18 and 19 are provided to prevent the viscous liquid from being thrown out of the mounting. Each of these seals comprises a highly flexible body portion in the form of a thin sleeve of rubber, synthetic rubber, or any suitable flexible material. Each end of the body portion is preferably provided with a somewhat thickened rim 20 at each end.

To assemble the mounting, the flexible sleeve 19 is sealed over the sleeve 11 so that one of the rims 20 is positioned as shown. One of the rims 20 of the seal 18 is then slid into its place over the skirt 15. Thereupon, the socket member 8 is slipped over the lower end of the funnel and the free end rim 20 of seal 19 is fitted into the shouldered portion provided at the top of the inner wall of well 14. Then the free end rim 20 of seal 18 is similarly slipped into its shouldered recess on the outer wall of well 14 and the parts are moved together so that the skirt 15 finds its operative position within the well 14. A passage 21 may be provided in the bearing member 12 for introducing the liquid into the well. A suitable stopper 22 may be provided to seal this passage after introduction of the liquid.

It is to be understood that changes and variations may be made without departing from the spirit and scope of the invention as defined in the appended claims.

I claim:

1. A self-centering mounting for a guide comprising a bracket, a socketed member in the bracket having a concave spherical bearing surface, an annular well in the socketed member adapted to receive a damping liquid, a floating bearing member adapted to receive and to be secured to the guide, said bearing member having a convex spherical bearing surface adapted to movably engage the concave spherical surface of the socketed member, the socketed member having a bore for receiving the guide, said bore hav-

ing a diameter greater than the diameter of the guide, the floating bearing member having a depending skirt extending into the well and spaced apart from the walls thereof at all points, the center of gravity of the assembly of guide and floating bearing member fixed thereto being substantially at the center of curvature of the spherical surfaces.

2. A self-centering mounting for a guide comprising a bracket, a socketed member in the bracket having a concave spherical bearing surface, an annular well in the socketed member adapted to receive a damping liquid, a floating bearing member adapted to receive and to be secured to the guide, said bearing member having a convex spherical bearing surface adapted to movably engage the concave spherical surface of the socketed member, the socketed member having a bore for receiving the guide, said bore having a diameter greater than the diameter of the guide, the floating bearing member having a depending skirt extending into the well and spaced apart from the walls thereof at all points, the center of gravity of the assembly of guide and floating bearing member fixed thereto being substantially at the center of curvature of the spherical surfaces, and sealing means between the socketed member and the floating bearing member to prevent loss of damping liquid.

3. A self-centering mounting for a guide comprising supporting means, an assembly movable relative thereto comprising the guide and bearing means thereon having a spherical bearing surface, said supporting means comprising a socket having a spherical bearing surface to co-operate with the first-mentioned surface and comprising a bore adapted to receive the guide, said bore having a diameter greater than the diameter of the guide, the center of gravity of the movable assembly being substantially at the center of curvature of the spherical surfaces, and means for damping the movement of the movable assembly comprising a liquid disposed between opposed surfaces inclined to the horizontal of the assembly and supporting means whereby movement of the assembly effects displacement of at least a portion of the liquid relative thereto.

4. A mounting for a guide of the type used to introduce filamentary material into rotating buckets comprising a supporting bracket, a socketed member in the bracket having a bore for receiving the guide, said bore having a diameter substantially greater than that of the guide, the socket of the member having a spherical bearing surface, a member on the guide having a spherical bearing surface adapted to co-operate with the spherical surface in the socket, the center of gravity of the guide being substantially at the center of curvature of the spherical surfaces, and means for damping movement of the guide relative to the socket comprising a liquid disposed between opposed surfaces of the two members whereby movement of the second member effects displacement of at least a portion of the liquid relative thereto.

5. A self-centering mounting for a guide comprising supporting means, an assembly movable relative thereto comprising a guide and bearing means thereon having a spherical bearing surface, said supporting means comprising a socket having a spherical bearing surface to co-operate with the first-mentioned surface and comprising a bore adapted to receive the guide, said bore having a diameter greater than the diameter of the guide, the center of gravity of the movable assembly being substantially at the center of curvature of the spherical surfaces, and means comprising a liquid body carried by the supporting means and into which a part of the assembly is partially immersed whereby movement of the assembly effects displacement of at least a portion of the liquid relative thereto for damping the movement of the movable assembly.
